CENTRIFUGAL CASTING MACHINE AND
METHOD

William D. Moore and Walter Morgan, Birmingham, Ala., assignors to Sand Spun Patents Corporation, New York, N. Y., a corporation of Delaware

Original application June 4, 1928, Serial No. 282,718. Divided and this application September 11, 1930, Serial No. 481,254

8 Claims. (Cl. 22—65)

This invention is an improvement in centrifugal casting machines and method, and more particularly in machines and method for producing relatively long hollow castings, such as cast iron pipes, either with or without bell and spigot ends, in a substantially horizontal mold.

One of the primary objects of the present invention is the provision of mechanism for properly charging the molten metal into the flask or mold, while it is horizontal, or substantially so.

Another object is the provision of a pouring trough or spout, of a character such as to direct the metal longitudinally of the mold to the remote end thereof within a minimum of time, and with a minimum of rebound and surging.

With these and other objects in view the invention consists in the construction and novel combination of parts fully described herein-after, illustrated in the accompanying drawing, and pointed out in the claims appended hereto, it being understood that various changes in the form, proportion, size and minor details of construction within the scope of the claims, may be resorted to without departing from the spirit of the invention.

In the drawing forming a part hereof:—

Fig. 1 is a side elevation, with parts in section, of the upper part of a centrifugal casting machine embodying the improvement.

Fig. 2 is an enlarged detail section, of the pouring trough and associated parts.

The improvements forming the subject matter of the present invention are shown in connection with that type of machine wherein refractory lined molds or flasks are used, and wherein a freshly lined mold is provided for each cast.

The mold or flask is supported for rotation in a substantially horizontal position, and a novel form of delivery spout is employed to perfect the distribution of molten metal longitudinally of the mold, without requiring movement of the machine between inclined and horizontal position.

This application is a division of our prior application Ser. No. 282,718, filed June 4, 1928 now Patent Number 1,783,094, and only such parts of the machine of the prior application are shown, as are necessary to an understanding of the invention. The improved machine includes a suitable frame 1, which is supported above a pit, not shown, the frame being supported by the walls of the pit, and the carriage or bed 2 for supporting the flask 3, is carried by the frame.

The carriage or bed has a pair of flask support rollers 4, which are journaled on the bed, the

pairs being spaced apart longitudinally, and the members of the pairs laterally. The rollers rotate on parallel axes, and they are designed to receive the flask 3 to be poured. The flask is rotated by a suitable motor 5, and the rotation may be controlled by the automatic controlling mechanism shown and described in the above mentioned application, if desired.

The molten metal is discharged into the mold from a ladle 6 arranged in a frame 7, which has oppositely extending pairs of pins 8 and 9. A support in the nature of a bracket, indicated generally at 10 is connected with the end of the frame 1, the connection being preferably a hinged connection indicated generally at 11, enabling the bracket to be swung away from the bed when desired.

The pins 9 of the frame 7 are adapted to engage one set of a plurality of sets of seats 12 in the upper face of the bracket 10, and the pins 8 are adapted to engage limiting blocks 13 on the bracket, when the ladle is in horizontal position. An arm 14 depends from the frame 7 at one side of the bracket, and this arm has a pin 15, which is adapted to seat in a fork 16, at one end of a strut 17, which as shown consists of two portions connected by a turn buckle or sleeve nut, thus enabling adjustment of the length of the strut.

The lower end of the strut is forked and engages a pin 18 in one end of a lever 19, pivoted at 20 to the pit wall, and the opposite end of the lever is connected by a link 21 with suitable mechanism, shown and described in the said prior application, for operating the ladle into tilted or normal position. The ladle normally occupies an upright position, and is tilted to the position shown in the drawing to empty the same, the molten metal being directed from the ladle into the flask or mold by means of a pouring trough or spout 22.

The bottom of this spout is so inclined that just enough impetus is imparted to the flowing metal to carry it to the remote or motor end of the flask in a stream of substantially uniform cross section, with very little or no rebound or surging. The impetus imparted to the molten metal by the inclination of the pouring spout is relied upon to obtain longitudinal distribution, and the inclination is calculated in accordance with several factors, such as the length of the pipe, whether or not the pipe is of the bell and spigot type, and the character and constants of the molten metal.

It has been found in practice, that with a metal of a certain fluidity, and with a known length of

110

pipe, the inclination of the spout may be so calculated that the inflowing stream will reach the bell or motor end of the flask within a selected time, with very little rebound, such as would 5 cause surging and disturbance of longitudinal distribution. The longitudinal distribution may be facilitated by so arranging the bed that the flask is slightly inclined toward the motor end. The 10 inclination, however, is insufficient to interfere in any way with the circumferential distribution from the centrifugal motion or spinning of the flask.

Referring to Fig. 2, it will be noted that the 15 bottom 23 of the trough or spout is provided with insets 24 and 25 of refractory material, at the point where the stream of metal from the ladle strikes. These insets are removable, if desired for any purpose, and materially lengthen the life 20 of the trough, while at the same time insuring that the inclination of the bottom will remain constant. The improved charging mechanism is adapted to be used with the apparatus forming the subject matter of our above mentioned application for patent, but it is apparent that it 25 might be used with other suitable apparatus if desired.

The bottom of the spout, that is, the surface 30 over which the molten metal flows from the tilting ladle to the mold, is formed on the arc of a circle, so that the direction of the flow of the metal from the ladle is gradually changed from substantially vertical to something near horizontal, without disturbance of the even uniform flow of the metal. Furthermore, by providing a 35 tilting ladle operated in the manner described, the metal is fed gradually and in a uniform stream to the spout, the cross section of the stream from the ladle being substantially the same from the moment when discharge begins until it is ended. 40 The arrangement of the ladle is such that the head of the metal discharged is substantially the same from the commencement to the end of the operation, and this is a feature of importance, in connection with the inclination of the spout bottom.

The impetus imparted to the molten metal is 45 such as to cause it to reach the remote end of the mold as quickly as possible without substantial rebound, and to attain a uniform level as quickly as possible. It will be apparent that the substantial absence of rebound and surging facilitates 50 the attainment of a uniform depth or uniform level in the mold. Because of the slight inclination of the mold, the greatest depth of metal will be at the bell end, where it is desired.

It has been found in practice that with the 55 character of metal, such as is usually used in our casting operations, an inclined surface for the spout formed on the arc of a circle having a two foot radius very nicely fulfills the conditions in casting pipe of sixteen foot length of the several diameters. That is, the ratio between the 60 length of the pipe to be cast and the radius of the circle upon which the incline is formed, is eight to one when casting pipes of 16 feet in length. This ratio will vary slightly with the 65 length of the pipe and with the characteristics of the metal. The more fluid the metal the less incline needed hence greater the radius, and the 70 greater the length of the pipe the greater the incline or smaller the radius.

What is claimed as new is:—

1. The method of casting hollow metal bodies 75 centrifugally in a refractory lined flask or mold, which consists in introducing the charge of mol-

ten metal at one end of a rotating mold while it is substantially horizontal with impetus just sufficient to cause the metal to flow to the opposite end of the mold without substantial rebound, and to cause said metal to lie on the bottom thereof in a mass of substantially uniform cross section prior to the centrifugal application of the metal to the mold wall. 80

2. In apparatus for centrifugally casting pipes, mechanism for introducing a charge of molten metal into one end and lengthwise of a substantially horizontal refractory lined flask or mold, including a spout having its bottom formed on an arc of a circle, the radius of said circle being with respect to the length of the pipe to be cast substantially in the ratio of one to eight units of measurement, said spout being inclined at an angle sufficient to effect flow of the metal through the mold from end to end without substantial rebound and in a stream of substantially uniform cross-section. 90

3. In centrifugal casting, mechanism for introducing a charge of molten metal into one end and lengthwise of a substantially horizontal refractory lined flask or mold, including a spout having the bottom thereof inclined at an angle such that impetus longitudinal of the mold will be imparted to the metal just sufficient to cause it to reach the opposite end of the mold and to attain a uniform level without rebound or surging, in substantial coincidence with the completion of the delivery of the metal from the spout, said angle being calculated from length of mold and fluidity of metal in inverse and direct ratios respectively. 100

4. The method of casting hollow metal bodies centrifugally in a refractory lined flask or mold, which consists in introducing the charge of molten metal into one end of a slowly rotating mold while it is substantially horizontal with impetus just sufficient to cause the metal to flow to the opposite end of the mold without substantial rebound and to cause said metal to lie on the bottom thereof in a mass of substantially uniform cross section prior to the centrifugal application of the metal to the mold wall, and then quickly accelerating the speed of rotation of the mold to apply the metal to the inner wall thereof centrifugally. 115

5. The method of casting hollow metal bodies centrifugally in a refractory lined flask or mold, which consists in charging the molten iron into one end of a slowly rotating mold while it is substantially horizontal over a surface inclined in accordance with the length of the mold and the characteristics of the molten iron, whereby impetus is imparted to the advancing stream of molten iron just sufficient to cause it to flow to the opposite end of the mold without substantial rebound and to lie on the bottom thereof in a mass of substantially uniform cross section prior to the centrifugal application of the metal to the mold wall, and then quickly accelerating the speed of rotation of the mold or flask to centrifugally apply the metal to the inner wall thereof. 130

6. In a centrifugal casting machine and in combination, a refractory-lined flask and means for supporting the same for rotation in a substantially horizontal position, means for rotating the flask, mechanism for introducing a charge of molten metal into one end and lengthwise of said flask while the latter is rotated at a relatively slow or non-centrifugal speed, said mechanism including a spout having the bottom thereof in- 145

clined at such an angle with relation to the length and position of the flask that the impetus imparted to the molten metal flowing over the spout into the flask is such as to cause the metal stream to reach the remote end thereof without substantial rebound, and means for accelerating the speed of rotation of the flask to centrifugally apply the metal to the inner wall thereof.

7. In apparatus for centrifugally casting pipes 10 of approximately sixteen feet in length, mechanism for introducing a charge of molten metal into one end and lengthwise of a substantially horizontal refractory-lined flask or mold, including a spout having a portion of its bottom positioned at an inclination corresponding substantially to the arc of the segment of a circle having a 2' radius and operating to deliver the metal stream to the far or remote end of the mold or flask without substantial rebound, and in a 15 stream of substantially uniform cross section.

8. In centrifugal casting and in combination, 20 a refractory-lined flask or mold and means for

rotating and supporting the same for rotation in a substantially horizontal position, mechanism for introducing a charge of molten metal into one end and lengthwise of the mold or flask while it is so supported, said mechanism including a spout having the bottom thereof on an incline corresponding substantially to the arc of a circle having a 2' radius, and a tilting ladle for delivering a stream of molten metal onto the inclined wall of the spout, the construction and arrangement of parts being such that the impetus imparted to the metal stream flowing down the inclined bottom wall of the spout will be just sufficient to cause the stream to reach the remote end of the mold or flask and to attain a substantially uniform level on the bottom thereof without substantial rebound or surge, and means for then accelerating the speed of rotation of the mold or flask to apply the metal to the inner wall thereof.
